BEATER ENGINE

Filed June 28, 1928

UNITED STATES PATENT OFFICE

WILLIAM V. KNOLL, OF DAYTON, OHIO, ASSIGNOR TO MIDWEST-FULTON MACHINE COMPANY, OF DAYTON, OHIO, A CORPORATION OF OHIO

BEATER ENGINE

Application filed June 28, 1928. Serial No. 288,858.

My invention relates to beating engines for the treatment of pulps and fibers for paper making and the like, and more particularly to a continuous flow apparatus 5 wherein the fined pulp or finished product is continuously removed by centrifugal action, while a supply of untreated material is being added to the quantity operated upon in the beating engine.

10 While centrifugal action has heretofore been utilized for pulp separation usually by discharging the material from the periphery of the drum forwardly beneath the hood onto a screen by which the fine and 15 coarse particles are separated, the present construction discharges the material rearwardly and takes advantage of the specific gravity or difference in weight of the particles in pulp to effect more thorough separation of the product, and more even grad- 20 ing of the fined or finished pulp whereby the output will be of uniform character.

The present beater engine is of the Hollander type and is provided with a receiver 25 trough or collecting pan located transversely of the engine and parallel with the drum but spaced rearwardly of the backfall and above the level thereof a sufficient distance to permit the heavier particles of pulp dis- 30 charged by centrifugal influence from the beater drum to fall by gravity back into the pulp stream flowing over the backfall, while the refined and finished portion of the pulp discharged from the rotating drum as a 35 spray over and beyond the heavier falling articles are collected in the receiving trough in which operates a screw conveyor, by which the collected material is conveyed beyond the beater engine or into a succeed- 40 ing beater engine of a series. An adjustable deflector is provided for the flying pulp particles whereby the quantity and character of the discharged material may be regulated.

45 The object of the invention is to simplify the structure, as well as the means and mode of operation of pulp separating and grading apparatus whereby it will not only be cheapened in construction, but will be more efficient in use, positive in operation, uni-

form in action, easily controlled and unlikely to get out of repair.

A further object of the invention is to provide means for utilizing centrifugal action in the separation of the fined or finished pulp from the coarser portions thereof and to further grade the material according to the specific gravity or weight of the particles.

A further object of the invention is to provide an improved form of continuous flow beater system wherein the material is fed progressively from one beater engine to another when it has been reduced to a predetermined state of refinement.

A further object of the invention is to provide an improved relation of a collecting receptacle for refined pulp with the beater drum and backfall of a typical beating engine.

A further object of the invention is to provide an improved method or process of pulp separation.

With the above primary and other incidental objects in view as will more fully appear in the specification, the invention consists of the features of construction, the parts and combinations thereof, and the mode of operation, or their equivalents, as hereinafter described and set forth in the claims.

Referring to the accompanying drawings, Fig. 1 is a side elevation of a typical Hollander beating engine to which the present invention has been applied. Fig. 2 is a plan view of a continuous flow system embodying the present invention wherein the refined pulp is progressively fed from one beater engine to another.

Like parts are indicated by similar characters of reference throughout the several views.

In the accompanying drawings, 1 is the vat or tub having therein a mid-feather 2 forming a circuitous path for the flow of pulp being treated. Located in one of the side channels of the engine is a rotary beater drum 3 co-operating with the usual bed plate 4 to reduce the fibers of the pulp which is passed between the roll and bed plate.

Located at the rear of the rotary drum 3 is the usual backfall 5 over which the treated pulp raised by the action of the drum flows, preparatory to again completing the circuit of the beating engine for repetition of the operation. Enclosing the drum 4 is the usual hood 7. Such is the usual construction of a typical Hollander beater engine which per se, forms no part of the present invention.

Extending upwardly and rearwardly from the hood 7 is a housing 8 within the rear portion of which is a collecting trough or receiver pan 9. This collecting or receiving compartment 9 is located somewhat above the level of the backfall 5 and is spaced rearwardly therefrom a sufficient distance to permit the free passage of fine portions of pulp which may be carried upward above the normal flow stream by centrifugal influence, but which are yet too coarse and too heavy to be discharged as finished material.

As the beater drum 3 rotates the major quantity of the pulp flows in a normal stream over the top of the backfall down the incline into the return channel of the beater engine. However, there will be nevertheless a considerable quantity of beaten pulp which by adherence to the rotating drum will be carried above the liquid level of the flowing stream traversing the backfall 5 and will be discharged upwardly and rearwardly from the drum by centrifugal force in the form of a spray. The coarse or heavy particles of this pulp spray unfit for discharge from the beating engine have not sufficient momentum to carry them a great distance and hence their trajectory will be very short and they will fail to reach the collecting or receiving receptacle 9. More finely reduced and lighter portions of the pulp being discharged through a higher trajectory and achieving longer flight will fall into the receiving or collecting receptacle 9 whereas the heavier and coarse portions return to the flowing pulp stream intermediate such receptacle and the backfall.

Interiorly of the housing 8 there is pivoted an arcuate deflector plate 11, the free edge of which is normally spaced a considerable distance above the margin of the collecting trough or receiving pan 9. This deflector plate or vane 11 is adjustable by means of the screw stem 12 to vary its relation with the margin of the collector receptacle 9, thereby varying the height of the inlet opening to such receptacle. By adjusting this deflector plate a greater or less quantity of material may be permitted to enter this collector receptacle for discharge from the engine. Likewise the character of the material will vary with its quantity. The collector receptacle 9 extends transversely of the beater engine parallel with

the rotating drum 3 substantially the full width thereof. The side of this receptacle 9 is inclined upwardly and laterally toward the beater drum. Beyond the limit of the drum the side wall is extended vertically as at 13 to form a conveyor trough by which the collected pulp is conveyed to the next beater engine of a series or to a tank or other receptacle as may be desired. A screw conveyor 14 extends through the collecting receptacle 9 and the continuing conveyor trough and serves to move the material which may be too dense or heavy to flow by gravity. However, if so desired the trough portion may be inclined, as may also the receiving receptacle 9 to induce a gravity flow of the collected material from one beater engine to another, or from the beater engine to a receiver tank. In Fig. 2 there is shown a succession of beater engines to which the present invention has been applied. The pulp discharged from the drum 3 of each engine into the adjacent collecting receptacle 9 is conveyed through the trough continuation of such receptacle by the screw conveyor to the succeeding beater engine. This discharge conduit has in its bottom an outlet opening 15 coincident with the return channel of the succeeding beater engine through which the pulp is discharged into such beater engine for retreatment. Thus the fined product resulting from each operation is collected in the receiving compartment and conveyed to the next beater engine of the series.

By locating the collecting receptacles to the rear of the beater drum and discharging material by centrifugal influence from the drum towards such receptacle the fined or finished product is automatically separated from the coarser or unfinished material by influence of gravity. Such coarse or unfinished material being too heavy to be projected the distance necessary for its reception in the collecting receptacle falls back into the flowing stream of pulp for reworking, while only the fine and completely finished material which is sufficiently light to be projected a greater distance by centrifugal action reaches the receiving or collecting receptacle and is conveyed from the beater engine. At the same time a new supply of material is being introduced into the beater engine through the conveyor trough discharging through the outlet 15 into the return channel of the engine.

From the above description it will be apparent that there is thus provided a construction of the character described, possessing the particular features of advantage before enumerated as desirable, but which obviously is susceptible of modification in its form, proportions and arrangement of parts, without departing from the principle involved or sacrificing any of its advantages.

While in order to comply with the statute the invention is described in language more or less specific as to structural features, it is to be understood that the invention is not limited to the specific details shown, but that the means and construction herein disclosed comprise the preferred form of several modes of putting the invention into effect, and the invention is therefore claimed 10 in any of its forms or modifications within the legitimate and valid scope of the appended claims.

Having thus described my invention, I claim:

- 15 1. The combination with a beater engine including a beater roll and a backfall, of a conveyor trough located in spaced relation with the roll and beyond the backfall, said trough being located within the range of a portion of the pulp discharged by centrifugal influence from the periphery of the roll, and a deflector plate overhanging the path of discharged pulp and adjustable from above into intercepting relation with the 25 centrifugally actuated pulp stream, a portion of which is received in the trough and conducted thereby beyond the beater engine.
2. The combination with a beater engine including a beater roll and a backfall, of a conveyor trough located in spaced relation with the roll and beyond the backfall, said trough being located within the range of a portion of the pulp discharged by centrifugal influence from the periphery of the roll, and receiving a portion thereof, and a deflector plate positioned above the level of said trough and adjustable toward and from the trough to vary the extent of the intermediate opening through which the pulp is 40 discharged into said trough and a screw conveyor located in said trough for discharging through the trough and beyond the beater engine, such portion of the pulp as may be received in said trough.
- 45 3. The combination with a beater engine including a beater roll and a backfall, of a conveyor trough located in spaced relation with the roll and beyond the backfall, said trough being located within the range of a portion of the pulp discharged by centrifugal influence from the periphery of the roll and an adjustable guide plate directing a portion of the discharged pulp into said trough.
- 55 4. The combination with a beater engine including a beater roll and a backfall, of a conveyor trough located in spaced relation with the roll and beyond the backfall, said trough being located within the range of a portion of the pulp discharged by centrifugal influence from the periphery of the roll, and an adjustable deflector co-operating with the trough and by its adjustment directing a greater or less quantity of the 60 centrifugally discharged pulp into the trough.

5. The combination with a beater engine including a roll and a backfall, of a pulp receiver located in substantially parallel spaced relation with the roll and beyond the backfall into which a reduced portion of the pulp is discharged from the periphery of the roll by centrifugal influence and means for varying at will the quantity of discharged material entering the receiver.

6. The combination with a beater engine including a roll and a backfall, of a pulp receiver located in substantially parallel spaced relation with the roll beyond the backfall and beyond the trajectory range of unfinished portions of pulp discharged by centrifugal influence from the periphery of the roll, and collecting the centrifugally discharged finished portions of the pulp and manually adjustable means for varying the collecting capacity of the receiver.

7. In an apparatus of the character described, means for causing an aerial discharge of pulp of mixed grades, whereby different grades will have different trajectory ranges and means for utilizing such variation of the trajectory range for grading the pulp including separate receivers located different distances from the point of discharge into which different portions of pulp of different grades fall by gravity.

8. A beating engine including a tub, a beater roll and a backfall over which the pulp is discharged by the action of the beater roll, characterized by a receiver for finished pulp located in spaced relation above the level of and beyond the backfall into which a limited quantity of the pulp is discharged by centrifugal influence from the periphery of the roll, said receiver being positioned sufficient distance from the roll to permit unfinished portions of pulp discharged from said roll by centrifugal influence to fall into the pulp stream flowing over the backfall and a curved plate pivoted above the path of discharge of the pulp and capable of swinging motion into and out of the pulp stream for varying the quantity of pulp reaching the receiver.

9. The combination with a beater engine including a beater roll and backfall, of a pulp receiver located in spaced relation with the drum and beyond the backfall into which a reduced portion of the pulp discharged from the periphery of the roll by centrifugal influence is received, and adjustable means for regulating the discharge.

10. The combination with a beater engine including a beater roll and backfall, of a pulp receiver located in spaced relation with the drum and beyond the backfall into which a reduced portion of the pulp discharged from the periphery of the roll by centrifugal influence is received, and an adjustable deflector for diverting a greater or

less proportion of the discharged pulp into said receiver.

11. The combination with a beater engine including a beater roll and a backfall, of a conveyor trough located in spaced relation with the roll and beyond the backfall, a hood extending from the roll over and enclosing the conveyor trough, said trough being located within the range of and receiving a portion of the pulp discharged by centrifugal influence from said roll and beneath said hood, which received pulp is discharged through said trough from the beater engine and an adjustable top in said hood adapted to be raised and lowered relative to the pulp stream beneath which the discharged pulp enters the trough.

12. In a system of pulp preparation, a series of beater engines, each having a beater roll, a continuous conveyor common to the several beater engines of the series, said conveyor being located beyond the backfall in spaced relation with the several beater rolls, there being ample intervening space between the rolls and conveyor through which coarse and unfinished pulp centrifugally discharged from the roll with limited trajectory may fall by gravity into the pulp stream of the engine, said conveyor being located beyond the trajectory of such coarse and unfinished pulp particles but within the range of trajectory of pulp discharged by centrifugal influence from the periphery of the several rolls and receiving pulp simultaneously therefrom, and a discharge outlet from said conveyor of each of the several beater engines, whereby pulp centrifugally discharged from the periphery of the roll of one engine is discharged into another beater engine of the series.

13. In a system of pulp preparation, a plurality of beater engines, each including a beater roll, simultaneously discharging coarse and fined pulp material from the periphery thereof, conveyor means connecting succeeding beater engines of the plurality one with another, said conveyor means between succeeding engines being located within the range of pulp centrifugally discharged from the roll of one engine and received in said conveyor and discharging the received pulp into the succeeding beater engine.

14. In a system of pulp preparation, a plurality of beater engines, a continuous screw conveyor common to the succession of beater engines, means for simultaneously discharging pulp from each engine of the plurality said parts being disposed to effect screenless separation of the coarse and fine portions of the pulp, the latter being received into said conveyor, said conveyor having a series of discharge outlets through which the collected pulp is discharged into the next beater engine of the plurality.

15. In a system of pulp preparation, a plurality of beater engines, each including a beater roll from which both coarse and fined pulp particles are simultaneously discharged by centrifugal influence, a conveyor system progressively connecting the beater engines in series and conveying segregated pulp portions from one beater engine to another, and means for segregating and delivering pulp portions into said conveyor system by centrifugal influence.

16. The herein described method of grading pulp and the like, consisting in discharging the material by centrifugal influence toward a distantly located receptacle whereby the heavier particles will fail to reach such receptacle and will fall into the supply body for reworking while only the lighter materials will be received in said distantly located receptacle.

17. The herein described method of grading pulp under influence of gravity consisting in discharging the pulp in aerial flight whereby pulp portions of different weight will be given different trajectory range and positioning pulp receiver at a distant point corresponding to the trajectory range of the predetermined grade of material.

18. The herein described method of grading paper pulp and the like, consisting in projecting a stream of pulp of mixed grades and allowing such material to fall by gravity, whereby pulp of different specific gravity will fall at different distances from the point of discharge and segregating the pulp falling at a predetermined distance from the point of discharge.

19. The herein described method of grading pulp, and the like, consisting in discharging the pulp material centrifugally from a beater roll, thereby giving to pulp of different grade different trajectory ranges and segregating the pulp portions having different predetermined ranges.

20. A beating engine including a tub, a beater roll and a backfall over which the pulp is discharged by the action of the roll, characterized by a receiver for finished pulp located in position to receive therein lighter portions of pulp discharged by centrifugal influence from the periphery of the roll, said receiver being located beyond the trajectory range of unfinished portions of pulp discharged from the roll by centrifugal influence.

21. The process of conditioning pulp for paper making, and the like, consisting in beating the pulp in a beater engine in which is maintained a constantly flowing pulp stream projecting a portion of the beaten pulp above the level of the flowing pulp stream and separating the elevated portion by gravity, and segregating the distantly

projected portions for discharge from the beater engine and permitting the less distantly projected portions to return to the pulp stream.

5 In testimony whereof, I have hereunto set my hand this 18th day of May A. D. 1928.

CERTIFICATE OF CORRECTION.

Patent No. 1,817,749.

Granted August 4, 1931, to

WILLIAM V. KNOLL.

It is hereby certified that error appears in the printed specification of the above numbered patent requiring correction as follows: Page 4, line 41, claim 13, beginning with the word "In" strike out all to and including the word "influence" line 76, of claim 15, and insert the following as claims 13, 14, and 15: -

13. In a continuous system of pulp preparation, a plurality of beater engines, each including a beater roll simultaneously discharging coarse and fined pulp material from the periphery thereof of a continuous conveyor means common to the plurality of beater engines connecting succeeding beater engines of the plurality one with another, said conveyor means being located beyond the trajectory range of coarse and unfinished pulp particles and within the range of fined pulp simultaneously discharged centrifugally from the roll of one engine and received in said conveyor, and discharging the received pulp into the succeeding beater engine.

14. In a system of pulp preparation, a plurality of beater engines, each including a beater roll, a continuous conveyor common to the succession of beater engines, means for simultaneously discharging coarse and fined pulp centrifugally from the beater roll of each engine of the plurality, said parts being disposed to effect screenless separation of the coarse and fine portions of the pulp, the latter being received into said conveyor, said conveyor having a series of discharge outlets through which the collected pulp is discharged into the next beater engine of the plurality.

15. In a system of pulp preparation, a plurality of beater engines, each including a beater roll from which both coarse and fined pulp particles are simultaneously discharged by centrifugal influence, a continuous conveyor system common to all of the beater engines of the plurality, said conveyor system having both intake and discharge communication with each of the succeeding beater engines of the plurality progressively connecting the beater engines in series and conveying segregated pulp portions from one beater engine to another, and screenless means for segregating the coarse from the fine material and delivering the fine pulp portions into said conveyor system by centrifugal influence.

and that the said Letters Patent should be read with these corrections therein that the same may conform to the record of the case in the Patent Office.

Signed and sealed this 12th day of April, A. D. 1932.
